GASTON ADELIN MATHIEU, OF LONDON, ENGLAND, ASSIGNOR TO RADIO CORPORATION OF AMERICA, A CORPORATION OF DELAWARE

ANTENNA SYSTEM

Application filed February 3, 1927, Serial No. 165,535, and in Great Britain February 27, 1926.

This invention relates to wireless receiving aerial systems and circuits therefor, and more particularly to a feeder arrangement by means of which energy received by a plurality of aerials may be rendered cumulative and fed to a "terminal tank circuit" which may constitute the input circuit of a wireless receiver.

According to this invention the energy received upon a pair or a plurality of pairs of aerials is rendered cumulative for each pair in intermediate or auxiliary feeders by means of twin transformers, the energy in pairs of the said feeders being similarly rendered cumulative in further intermediate or auxiliary feeders, and so on, until the energy received upon all the aerials is rendered cumulative in a single receiving or "terminal tank circuit".

Preferably the twin transformers each comprise two primaries and two secondaries, and a capacitative reactance such as will substantially balance the inductive reactance of one of the secondaries.

In one arrangement as applied to a receiving installation having two aerials, the energy received upon each aerial is fed into a twin wire auxiliary feeder, preferably through aerial transformer. In general, such aerial transformers will be necessary not only to provide coupling but also owing to the fact that the surge impedances of the auxiliary feeders will probably differ widely from the impedances of their associated aerials.

These aerial transformers may be conveniently formed as auto-transformers, the twin wires of the auxiliary feeders being tapped upon an inductance in the aerial circuit, and the said aerial being earthed preferably midway between the tappings. The two auxiliary feeders are each connected to one of the primaries of a twin transformer having two primaries and two secondaries, and the secondaries of the said twin transformer are

connected in series through a condenser of such size that its capacitative reactance substantially balances the inductive reactance of one secondary winding, and supplies energy to a twin wire main feeder which in turn supplies energy to the "tank" circuit. The

twin wires of one of the auxiliary feeders should be crossed over between its associated aerial and the twin transformer, so that the said transformer will add vectorially the voltages fed to it from the auxiliary feeders.

The ratio of transformation of the twin transformers should be such as to provide for the correct impedance of the main working in series at the junction point. For example, if the surge impedances of the auxiliary feeders and the main feeder are equal, the transformer should have a step down ratio of 2:1 towards the "tank" circuit. Similarly, the effective impedance of the "tank" circuit should be substantially equal to the surge impedance of the main feeder, so as to avoid reflection and obtain maximum transfer into the said circuit.

If desired, in place of twin wire auxiliary feeders there may be employed auxiliary feeders of any other suitable type.

The invention may be extended to any number of pairs of aerials. For example, in the case of four aerials, there will be four aerial transformers supplying four auxiliary feeders whose energy is rendered cumulative in pairs, by means of two twin transformers which in turn supply two further auxiliary feeders which transfer their energy through another twin transformer into the main feeder and "tank" circuit.

The invention will be further explained and illustrated with reference to the accompanying drawings, of which Figure 1 is a schematic diagram of a general arrangement in accordance with the invention; Figures 2, 3 and 4 are explanatory diagrams, and Figures 5, 6 and 7 are further diagrams showing arrangements in accordance with the invention.

Referring to Figure 1, A are aerials; T^1 , T^2 and T^3 transformers; Z the final receiving or "tank" circuit; and W^1 , W^2 and W^3 connecting cables. The transformers T^1 are required each to act as coupling means and also to match the impedance of its associated aerial A with the surge impedance of its associated connecting cable W^1 ; transformers T^2 are each required to add vectorially the voltages transmitted to it by its associated cables

W¹, while the transformer T³ is required to add vectorially the voltages transmitted to it by its associated cables W². The arrangement is shown in greater diagrammatic detail in Figure 6, in which it will be seen that the transformers T² and T³, are twin transformers. In each of these transformers the secondaries are connected in series through condensers C which are adjusted to balance the inductive reactance of one of the secondary windings, so that by suitably adjusting the ratio of transformation of the transformers T¹ maximum transference of energy from the aerials may be obtained while the whole system is balanced.

Figure 7 illustrates two aerials of a receiving aerial system feeding via transformers T¹ through a twin transformer T² and thence through an intermediate feeder W² and thence ultimately to a "tank" circuit.

Examination of the arrangements shown in Figures 1, 6 and 7, will reveal that they constitute in effect perfectly balanced three wire systems with the neutral wire removed. This will appear more clearly from Figures 2, 3, 4 and 5. Referring to Figure 2, this shows the aerials represented as alternators A each feeding through a transformer T¹ and cables W¹ to a receiver Z. Assuming the transformer T¹, cables W¹ and receivers Z to be similar, the same power can be transmitted by means of two three wire systems as shown in Figure 3, or a single three wire system as shown in Figure 4. In the double system of Figure 3 the voltage across the outer lines will be obviously equal to the sum of the voltages across two of the receivers Z, while in the system of Figure 4 the voltage across the outer lines will similarly be equal to the sum of the voltage across all the receivers Z. In both cases, assuming perfect balance, no current will flow in the neutral wires N and these wires may therefore be removed. This leads logically to the arrangement shown in Figure 5, in which the neutral wires are removed, and to the already described arrangements of Figures 6 and 7.

Obviously systems in accordance with this invention may be employed for transmitting as well as for receiving.

Having thus particularly described the nature of my invention what I claim is:—

1. A wireless system comprising a plurality of pairs of aerials, intermediate and auxiliary feeders, a terminal circuit and means comprising twin transformers each of which has two primaries and two secondaries the latter being connected in series for rendering cumulative the energy from each pair of aerials in said intermediate or auxiliary feeders, and similar means for rendering cumulative the energy from pairs of intermediate and auxiliary feeders and so on until the energy from or to all the aerials is rendered cumulative in said terminal circuit.

2. A wireless system comprising a plurality of pairs of aerials, intermediate and auxiliary feeders, a terminal circuit, means comprising twin transformers each having two primaries and two secondaries, the latter being connected in series through a capacitive reactance such that the inductive reactance of one secondary is substantially balanced, for rendering cumulative the energy for each pair of said aerials in said intermediate or auxiliary feeders, and means for rendering cumulative the energy from pairs of intermediate and auxiliary feeders and so on until the energy from or to all the aerials has been cumulated in said terminal circuit.

3. A wireless system comprising a plurality of pairs of aerials, an auto-transformer associated with each aerial, twin transformers each having a pair of primaries coupled through said auto-transformers to each pair of aerials and a pair of secondaries connected in series, a twin transformer associated with the first mentioned transformers for rendering cumulative the energy from each pair of aerials, and a utilization circuit associated with the last mentioned transformer.

4. A wireless system comprising a plurality of pairs of aerials, intermediate or auxiliary feeders, a single terminal tank circuit, means comprising twin transformers each having two primaries and two secondaries the latter being connected in series through a condenser for rendering cumulative the energy from each pair of aerials in said intermediate or auxiliary feeders, and means for rendering the energy so obtained cumulative in said single terminal tank circuit.

5. A wireless system comprising a plurality of pairs of aerials, means comprising twin transformers the primaries of which are connected to the aerials and so arranged that their secondary windings, connected in series through a capacity, add vectorially the voltages fed to them by the aerials, means for rendering cumulative the energy obtained from the twin transformers and means for feeding the energy so obtained to a receiving circuit.

6. A wireless system comprising a plurality of pairs of aerials, an inductance in each of said aerials, a twin transformer having a pair of primaries, and a pair of secondaries, associated with each pair of aerials, connecting means between each of said primaries and one of said aerials, a second transformer having a plurality of primaries and secondaries, means for connecting each pair of secondaries of said first named transformers in series with a primary winding of said last named transformers, a tank circuit, and means connecting the secondaries of said last named transformers in series with the input of said tank circuit.

7. A wireless system comprising a plurality of pairs of aerials, intermediate or aux-

iliary feeders, an auto-transformer associated with each of said aerials, means comprising twin transformers for rendering cumulative the energy from each pair of aerials in said intermediate or auxiliary feeders the surge impedance of which is matched to the surge impedance of the aerials and auto-transformers, means for rendering cumulative the energy from pairs of intermediate and auxiliary feeders; a tank circuit; and main feeders, the surge impedance of which is matched to the surge impedance of said intermediate or auxiliary feeders connecting said last named means to the tank circuit.
